CONRAD H. HAASE, OF NEW ORLEANS, LOUISIANA, ASSIGNOR OF ONE-FOURTH TO
WILLIAM H. WOOD, OF DALLAS, TEXAS.

COMBINED PENCIL HOLDER AND SHARPENER.

941,518.

Specification of Letters Patent. Patented Nov. 30, 1909.

Application filed May 23, 1908. Serial No. 434,686.

To all whom it may concern:

Be it known that I, CONRAD H. HAASE, a citizen of the United States, residing at New Orleans, in the parish of Orleans and State 5 of Louisiana, have invented certain new and useful Improvements in Combined Pencil Holders and Sharpeners, of which the following is a specification.

This invention relates to pencil sharpeners, and has for its object to provide an improved device of this kind which may also be placed over the point of the pencil to protect it when not in use; and to this end the invention consists in a novel arrangement 10 and combination of parts to be hereafter described and claimed.

In the accompanying drawing, Figure 1 is a longitudinal section of the device assembled. Fig. 2 is an elevation of the case or 20 tube which receives the pencil. Fig. 3 is an elevation of the sleeve whereby the pencil is advanced and retracted. Fig. 4 is a cross-section on the line 1—2 of Fig. 3. Fig. 5 is an elevation of the sharpener. Fig. 6 is a 25 cross-section on the line 3—4 of Fig. 5. Fig. 7 is an elevation of the complete holder and sharpener. Fig. 8 is a cross-section on the line 5—6 of Fig. 1. Fig. 9 is an elevation of a modified form of sharpener.

Referring specifically to the drawing, A 30 is a case or tube of suitable length into which the pencil is placed. The tube is angular in cross section and receives a pencil which is also angular in cross section so that the 35 pencil cannot rotate therein but is free to slide up and down in the tube. On one end of the tube A is mounted a sleeve B which projects a short distance from the tube and has in said projecting portion interior 40 threads f which are stamped into the body of the sleeve. Adjacent the end of the tube A is a circular flange l over which fits a rim e on the inner end of the sleeve B whereby said sleeve is secured to the tube against 45 lengthwise separation but is free to rotate thereon.

The sharpener is a tube C which fits on the sleeve B and projects a suitable distance beyond the outer end thereof, said projecting end of the sharpener being cone-shaped and having one or more slits g. The slits 50 have one of their edges bent inwardly to act as a cutter for trimming the wooden casing of the pencil to a point. The extreme end 55 of the sharpener has crossed slits h and n,

respectively, so that when the point of the pencil reaches it and the pencil is continued to be fed forwardly, said end will spread apart to expose the point of the pencil ready for use. The edges of the slits h and n cut 60 or scrape the exposed end of the lead and point it. The butt-end of the tube C has longitudinal slots o which receive tongues m struck up from the sleeve B, so that said tube and sleeve will rotate together when 65 the tube is rotated. The tube however can be slipped off the sleeve lengthwise in order to remove the stump of the pencil from the tube A.

On the butt-end of the tube A may be 70 placed a rubber cap D to serve as an eraser, and the outer surface of the tube may be suitably ornamented, or used to display an advertisement.

In use, the pencil is inserted into the tube 75 A at the rear end thereof by removal of the cap D and pushed forwardly until the threads f will bite into the wooden casing of the pencil when the sleeve B is rotated by the tube C. The threads f indent the wood 80 of the pencil and form threads therein, thereby operating to feed the pencil forwardly or to retract the same when the sleeve is rotated. To sharpen the pencil the tube C is turned in a direction to feed the pencil 85 forwardly. The cutters g trim the wooden casing of the pencil to a point, and as the pencil is continued to be fed forwardly the slits h and n at the extreme end of the tube spread apart and expose the point of the 90 pencil ready for use, the edges of the slits cutting or scraping the lead and pointing it. When the pencil is not in use the point may be drawn back into the tube by rotating the same in a direction to retract the pencil. 95

The device herein described is simple in construction and can be cheaply produced. It can be applied to any ordinary pencil or marking crayon and it is easy to operate to sharpen the pencil or to withdraw it into 100 the tube C. The pencil can be used up to a very short stump which is readily removed upon slipping the tube C off the sleeve B. In the drawing I have shown three cutters g which if put in a line would cover substantially the entire length of the cone-shaped portion of the tube C, but a similar result may be had by more or less cutters, of course in such cases the cutters being longer or shorter according to their number. 105 110

In Fig. 9 is shown a modified form of sharpener. In this case the sleeve B is dispensed with and the sharpening-tube C' is applied directly to the case or tube A in the same manner as the sleeve B. The threads ⁵ for advancing or retracting the pencil are on the sharpening-tube. This form of sharpener operates in the same manner as the one first described: viz., by turning either the tube C' or the tube A. In the modified form of sharpener the stump of the pencil is removed by turning the tube A or C' rearwardly until the stump is released from the threads after which it can be easily shaken out of the butt-end of the tube. ¹⁰

The holder may be used without the sharpener for the purpose of giving the pencil a uniform length throughout its whole use, and to be able to use it up to a very short ²⁰ stump, and to be able by a return movement of the sleeve B to protect the point of the pencil. Of course, in this case the pencil will have to be sharpened either with a knife or by other means. The sharpener ²⁵ may also be used separately without the holder.

It is to be understood that various changes in minor details may be made, without departing from the spirit of, or sacrificing ³⁰ any of the advantages of the invention.

I claim:

1. A pencil-sharpener comprising a tubular casing receiving the pencil, a sleeve rotatably mounted on the casing and projecting from one end thereof, the projecting end of the sleeve having interior screw-threads engageable with the pencil, and pencil-sharpening means carried by the sleeve. ³⁵

2. A pencil-sharpener comprising a tubu-

lar casing receiving the pencil, a rotary ⁴⁰ sharpener carried by the casing and having a conical end projecting therefrom to inclose the end of the pencil, interior projecting cutters on said conical end, a sleeve rotatable on the casing, and having threads ⁴⁵ engaging the pencil for projecting the point of the pencil from the sharpener and for retracting the same thereinto, and means for preventing the sleeve from traveling. ⁵⁰

3. A pencil-sharpener comprising a tubular casing receiving the pencil, a sleeve rotatably mounted on the casing and projecting from one end thereof, the projecting end of the sleeve having interior screw-threads engageable with the pencil, and a ⁵⁵ pencil-sharpener comprising a tube mounted on the sleeve to rotate therewith, and having a cone-shaped end to receive the pencil point and provided with inwardly projecting cutters. ⁶⁰

4. A pencil-sharpener comprising a tubular casing receiving the pencil, a sleeve rotatably mounted on the casing and projecting from one end thereof, the projecting end of the sleeve having interior screw-threads engageable with the pencil, tongues projecting from the sleeve, and a pencil sharpener comprising a tube mounted on the sleeve and having a slit to receive the tongues, said tube having a cone-shaped end to receive ⁷⁰ the pencil and provided with inwardly projecting cutters. ⁶⁵

In testimony whereof I affix my signature, in presence of two witnesses.

CONRAD H. HAASE.
